United States Patent Office.

LAROY S. STARRETT, OF NEWBURYPORT, MASSACHUSETTS.

Letters Patent No. 73,847, dated January 28, 1868.

IMPROVEMENT IN SHOES.

The Schedule referred to in these Letters Patent and making part of the same,

TO ALL WHOM IT MAY CONCERN:

Be it known that I, LAROY S. STARRETT, of Newburyport, in the county of Essex, and State of Massachusetts, have invented a new and useful Improvement in the Mode of Lacing Boots and Shoes, of which the following is a full, clear, and exact description, reference being had to the accompanying drawings, making a part of this specification, in which—

Figure 1 is a view of a gaiter-boot, showing my improved mode of lacing.

Figures 2 and 3 represent studs and hooks for holding the lacing-string.

Figures 4 and 5 represent a device for securing the end of the lacing-string.

The object of my invention is to provide a simple, efficient, and expeditious means for lacing a boot or shoe; and the invention consists in the attachment, to each side of the opening of the shoe to be laced, of a series of hooks or buttons, which are securely fastened to the leather or other material, by means of rivets, and over or around which a single string, secured to the lower portion of the opening, is passed, from one side to the other, and fastened at the upper portion by a peculiarly-shaped device, in such a manner that the shoe may be very easily and expeditiously laced and fastened, and as easily unfastened and unlaced. Referring to the drawings—

Figure 1 represents my improved mode of lacing, as applied to a gaiter-boot.

a a' are fastenings, formed of metal or other hard suitable material, of the shape shown in figs. 2 and 3, and consisting of a bent or hook-shaped portion, *a*, and a projection, *a'*, and riveted, or otherwise firmly secured to the boot or shoe, at suitable intervals on each side of the opening. At one side of the upper portion of the opening is attached a fastening, of the shape shown in figs. 4 and 5, the same consisting of metal, having two curved ends or hooks, with a projecting stud in the centre, and is designed for securely fastening the end of the string or lacing, in the place of tying a knot in the same, as shown in fig. 5.

A single string or lacing being fastened at one end to the lower portion of the opening of the shoe, is passed alternately from one side to the other, over the hooked portions *a*, thus causing the two sides to be gradually and evenly drawn together, and at the upper end is secured to the fastening *b*, as shown in fig. 5, where it will be firmly held without tying.

The whole operation is very easily and expeditiously performed. When the boot or shoe is to be unlaced, the string is simply released from the fastening *b*, when it may, in a moment, be detached from the side fastenings *a a'*, without the necessity of untying the string, or incurring the risk of a hard knot. The object of the projection *a'* is to serve as a guard to prevent a lady's dress or other article from being caught in the hooks *a*, and also to prevent the string or lacing from slipping out. Instead of a hook, *a*, the fastening may be formed with a stud having a groove, for preventing the string from slipping off. The ordinary method of passing the string through eyelet-holes, takes considerable time, comparatively, it being necessary to adjust the strings to the several pairs of holes, in tightening them up.

Having thus described my invention, what I claim as new, and desire to secure by Letters Patent, is—

As an article of manufacture, the fastening *a a'*, when constructed and applied to a boot or shoe, as and for the purpose specified.

In testimony whereof, I have signed my name to this specification, in the presence of two subscribing witnesses.
